(57) **CLAIM**

The ornamental design for a camera mobile phone, as shown and described.

DESCRIPTION

FIG. 1 is a perspective view of a camera mobile phone, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an alternative perspective view of the camera mobile phone when the camera cell phone is folded; and,

FIG. 9 is an operational left side plan view thereof, showing an operation of opening the claimed design, wherein the rear cover has been rotated around to the front.
